UNITED STATES PATENT OFFICE

117,809

DESIGN FOR A COMBINED REFRESHMENT
STAND AND SHADE THEREFOR

Harry J. Hater, Cincinnati, Ohio, and Louis Macloon, Culver City, Calif., assignors to Foot-long, Inc., Cincinnati, Ohio, a corporation of Ohio

Application July 27, 1939, Serial No. 86,280

Term of patent 7 years

To all whom it may concern:

Be it known that we, Harry J. Hater and Louis Macloon, citizens of the United States and residents of Cincinnati, in the county of Hamilton and State of Ohio, and Culver City, in the county of Los Angeles and State of California, respectively, have invented a new, original, and ornamental Design for a Combined Refreshment Stand and Shade Therefor, of which the following is a specification, reference being had to the accompanying drawing, forming part thereof.

In the drawing:

Fig. 1 is a front elevational view of the combined refreshment stand and shade therefor, showing our design;

Fig. 2 is an end elevational view of the same, the shade element being shown broken away at its standard;

Fig. 3 is a rear elevational view of the refreshment stand portion of the design; and

Fig. 4 is an enlarged top plan view thereof.

The dominant feature of the design resides in the refreshment stand portion of the design shown in full lines.

We claim:

The ornamental design for a combined refreshment stand and shade therefor, as shown and described.

HARRY J. HATER.
LOUIS MACLOON.
